UNITED STATES PATENT OFFICE

2,612,067

SPANNER TYPE FLYWHEEL ROTATING
TOOL

Frank J. Brugmann, Greeley, Colo.

Application June 27, 1949, Serial No. 101,625

1 Claim. (Cl. 81—90)

1

This invention relates to improvements in tools for rotating flywheels of internal combustion engines.

In the assembly, disassembly, and repair of automobile and other internal combustion engines it is common practice to rotate the engine by hand to position certain of the operative parts thereof, the flywheel usually being grasped by a hand to apply the necessary torque. Most flywheels of modern engines are equipped with a ring gear on the flywheel with which a gear on the electric starter engages. The teeth of this gear, when grasped to turn the engine, often cut the hands of the mechanic. Moreover, if the engine is "stiff," that is, difficult to turn because of tight operative parts, the flywheel does not offer sufficient leverage to rotate the engine. Certain tools have been devised for engaging these flywheel teeth and to provide a handle or lever with which the flywheel may be more easily turned, and it is to tools of this type that the present invention more particularly relates.

One of the objects of the invention is to provide an improved flywheel rotating tool which securely locks to the flywheel teeth when torque is applied to the tool in one direction.

Another object is to provide a tool of the foregoing type which automatically releases from the teeth when torque is applied in an opposite direction.

Further objects are to provide a tool which is simple and rugged in construction, may be economically manufactured, and is efficient in operation.

Still further objects, advantages, and salient features will become more apparent from the description to follow, the appended claim, and the accompanying drawing, in which:

Figure 1 is a side elevation of the tool which forms the subject of the invention;

Figure 2 is a top plan as viewed from plane 2, Figure 1;

Figure 3 is a section taken on line 3—3, Figure 2;

Figure 4 is a section taken on line 4—4, Figure 2; and

Figure 5 illustrates the tool in position applied to a flywheel when in use.

Referring in detail to the drawing, wherein the invention is illustrated by way of exemplification, the tool comprises a lever 10 having a knurled hand grip portion 11 at one end and a rectangular portion 12, such as a square, at its other. A pair of arms 13, 13a are pivoted at their right ends (Figures 1 and 2) to the end of

2

portion 12 by means of a headed pin 14, such as a rivet, these arms being joined by a wall portion 15 at their left ends. A similar pair of arms, 16, 16a are pivoted by a rivet 17 to portion 12, near their left ends, and somewhat below rivet 14, these arms also being joined by a wall portion 18 at their right ends. A link 19 has one end disposed between an intermediate portion of arms 13, 13a and its other end between the outer ends of arms 16, 16a, the ends of this link being pivotally secured to the respective pairs of arms by pivot pins 20, 21, such as rivets. Either one of walls 15 or 18, or both, may be provided with an extension 22 which forms a stop to limit movement of the tool and flywheel when in use, this extension abutting a portion of the flywheel casting on certain automobile engines. It is to be understood that this stop is not essential to the invention in its broader aspects, and is only a refinement which may optionally be employed if so desired.

It will be observed that the distance between pivots 14, 17 and 20, 21 is the same and the distance between pivots 14, 20 and 17, 21 is the same, thus forming a parallelogram linkage system joining the walls 15, 18 to lever 10.

In the use of the device, walls 15, 18 are inserted between teeth of the flywheel 23 and with a slight force in the direction of arrow 24, Figure 5, the lever is rotated in the direction of arrow 25, this action drawing walls 15, 18 toward each other and firmly engaging the sides of teeth 26, 27, the angle of the walls relative to each other being teeth 26, 27, the angle of the walls relative to each other being so chosen that the walls will not slip from the teeth. With the added leverage the flywheel may be easily rotated in the direction of arrow 25 and when a new "bite" is required, the lever is moved slightly in the opposite direction whereupon it automatically disengages from the teeth. If it be desired to rotate the flywheel in the opposite direction to arrow 25, the tool is merely rotated 180° around the axis of the handle and applied to the teeth as previously described.

Having described the invention what I claim as new is:

An engine rotating tool comprising; a lever, a first arm pivotally connected directly to the lever adjacent one end of the latter and projecting laterally thereof in a first direction, a second arm pivotally connected directly to the lever in spaced relation to the first arm and projecting laterally of the lever in a direction opposite to

the first direction, the outer free ends of the arms being disposed beyond said end of the lever, gear tooth engaging means at the free ends of the arms constructed to engage angularly spaced teeth on the periphery of an engine flywheel, and a stop element extending outwardly from the gear tooth engaging means at the end of one of the arms forming a stop adapted to engage a stationary engine part to limit rotation in one direction.
